UNITED STATES PATENT OFFICE.

HOWARD M. DUDLEY, OF PHILADELPHIA, PENNSYLVANIA, ASSIGNOR, BY MESNE ASSIGNMENTS, TO THE FIFTH AVENUE BANK OF NEW YORK, OF NEW YORK, N. Y., A CORPORATION OF NEW YORK.

APPARATUS FOR DYEING, SCOURING, OR OTHERWISE TREATING YARN AND OTHER FIBERS IN THE HANK OR SKEIN.

Application filed August 5, 1921. Serial No. 489,934.

To all whom it may concern:

Be it known that I, HOWARD M. DUDLEY, a citizen of the United States, and a resident of Philadelphia, Pennsylvania, have invented certain new and useful Improvements in Apparatus for Dyeing, Scouring, or Otherwise Treating Yarn and Other Fibers in the Hank or Skein, of which the following is a specification.

10 My invention relates more particularly to that type of machine in which the hanks or skeins of yarn or fiber to be dyed or otherwise treated, are suspended from sticks and dip into a closed tank or chamber containing

15 the dyeing or treating liquid, and in which provision is made for moving such liquid; preferably in a plurality of directions in order that all portions of such skeins or hanks of yarn or other fibers shall be subjected equally to the action of the same.

A further object of my invention is to provide a vertically movable frame or support for the yarn-carrying sticks, such frame or support being so mounted within the 25 closed chamber that when the dyeing or treating liquid is being moved therein in one direction, it will have a tendency to lift said sticks, and the yarn with the same, and in such action will cause a separation between 30 the sticks and the yarn supported thereby at the point of contact, whereby such contacting portion, which is more or less difficult of access by the liquid, shall receive as great an amount of contact with the liquid as the 35 balance of the skein or hank.

A further object of my invention is the provision of means for retaining the yarn or fiber-carrying sticks in the frame or support therefor; which retaining means are 40 displaceable to permit ready insertion or removal of such sticks, and additionally are provided with means whereby they may be locked in the stick-retaining position.

These and other features of my invention 45 are more fully described hereinafter, reference being had to the accompanying drawings, in which:

Figure 1, is a longitudinal sectional view of one form of apparatus to which my invention may be applied; showing also one 50 form of means for effecting movement of the

dyeing or treating liquid in both directions therein disposed within a chamber of the apparatus.

Fig. 2, is a longitudinal sectional view of 55 another form of apparatus to which my invention may be applied; the means for effecting movement of the liquid being disposed externally of the tank.

Fig. 3, is a similar longitudinal sectional 60 view of another form of apparatus to which my invention may be applied; the means for effecting movement of the liquid being also disposed externally of the tank, but differing from the means shown in Fig. 2. 65

Figs. 4, 5 and 6, are sectional views on the lines IV—IV; V—V; and VI—VI, Figs. 1, 2 and 3, respectively.

Figs. 7, 8 and 9, are enlarged views illustrating my improved form of frame or support for the yarn or fiber-carrying sticks, in 70 plan and side elevations, respectively.

Figs. 10, 11 and 12, are cross-sectional views on the lines X—X; XI—XI and XII—XII, Fig. 8, respectively, and 75

Figs. 13 and 14, are diagrammatic views illustrating the position of the hanks or skeins of yarn or fiber with respect to the carrying sticks during the circulation of the dyeing or treating liquid in opposite directions. 80

In the structure illustrated in Fig. 1, 1 represents a closed vat or tank in which the skeins or hanks of yarn or fiber may be treated, and which may be divided into a pair of 85 chambers 2 and 3, by a partition 4; the chamber 2, constituting the hank or skein receiving chamber, and the chamber 3, containing a propeller wheel 5, the rotation of which serves to move or circulate the liquid 90 through said chambers 2 and 3, and in proper contact with the hanks or skeins of yarn or fiber suspended in said chamber 2.

The propeller wheel may be mounted upon a vertical shaft 6, passing through the cover 95 7, of the tank, and it may be provided with any suitable form of driving mechanism, with provision for driving the shaft in two directions. As may be readily understood, movement of said propeller wheel in the direction of arrow α will cause the liquid to move downwardly in the chamber 2 and up- 100

wardly in the chamber 3; passing under the partition 4, while movement of said propeller wheel in the direction of the arrow *b* will reverse the direction of flow of the dyeing or treating liquid.

5 A foraminous partition, which may comprise a series of cross bars 8, suitably mounted in side rails 9, extends between the partition 4 and the end wall of the vat or tank, at the lower portion of the chamber 2.

10 In accordance with the usual practice, the hanks or skeins of yarn or other fiber, indicated at X, are suspended from detachable sticks 10, which sticks are in turn supported by a suitable frame. This frame may comprise side rails 11, apertured at 12, to receive the ends of the yarn carrying sticks, and the ends of these side rails 11, are in turn mounted in box-like supports 13, disposed adjacent 15 the ends of the chamber 2; such rails being free to rise and fall within said box-like supports, for a limited extent under the influence of the liquid when the latter is moved through the respective chambers.

20 25 The sticks 10 are held against endwise movement by means of locking plates 15, extending longitudinally of the side rails 11, and supported by guide housings 16, carried by said rails; said plates and rails 30 being apertured or recessed at 17 and 18, respectively, for the reception of retaining pins 19, adapted to hold said locking plates in place. When it is desired to remove any one or more of the yarn carrying sticks, 35 these locking plates may be lifted and held in the upper part of the housings or guides 16 by said pins 19. As shown in Figs. 7, 8 and 9, I may employ round sticks, indicated at 10, or rectangular yarn-carrying sticks, 40 indicated at 10^a.

45 The pairs of box-like supports 13, at the respective ends of the chamber 2, and in which the ends of the side rails 11 are supported, may be connected together by cross bars 20, whereby said box-like supports and the yarn or fiber-carrying frame mounted therein may be bodily suspended within the chamber 2, by bolts 21, secured to the cover 7. In addition, supports 22, depend from 50 the box-like members 13; the lower ends of these supports 22 carrying rails 23, adjustably secured to said supports by pins 24, and having cross sticks 25, which pass through the lower portion of the hanks or 55 skeins of yarn or fiber and restrain the same from excessive upward movement when the liquid in the chamber 2 is caused to move in an upward direction.

60 Disposed above the yarn-carrying sticks is a foraminous partition comprising a plurality of cross bars 8^a, carried by rails 9^a, which may be mounted on the cross bars 20 connecting the box-like supports 13.

65 By providing a movable frame or rack for supporting the yarn-carrying sticks, the

latter are free to rise a limited extent when the liquid is circulated upwardly with respect to the skeins or hanks of yarn; the extent of such movement being clearly indicated in the diagrammatic views Figs. 13 and 14. By this means, the yarn is lifted at intervals from its contact with the sticks, thereby permitting full engagement by the dyeing or treating liquid, and avoiding the danger of stick marks frequently occurring 70 because of the close engagement of the skein or hank of yarn with the sticks by reason of the weight of the same when saturated with the dyeing or treating liquid.

75 In the type of structure illustrated in Fig. 1, I have shown a submerged propeller 5, as the means for moving or circulating the dyeing or treating liquid within the tank or vat. It will be understood, of course, that I may employ a plurality of 80 propellers instead of a single one, if desired, and that in this arrangement the liquid moving or circulating means are located 85 wholly within the main tank or vat.

90 In the structure shown in Fig. 2, the circulating means for the dyeing or treating liquid are disposed externally of the tank and they may comprise a conduit 26, communicating with a pair of passages 27 and 28, provided with valves 29 and 30, and 95 forming alternately inlet and discharge passages whereby the liquid may be moved in either direction in the dyeing or treating chamber as may be desired; a rotary pump 31, suitably driven, being preferably employed to move the liquid. The arrangement of the yarn-carrying sticks and accessories is substantially the same as illustrated in Fig. 1.

100 In the structure shown in Fig. 3, means 105 disposed externally of the tank or vat for moving the liquid through the dyeing or treating chamber in opposite directions are also shown. Such means preferably include a casing 35 of special character, having a 110 mid section 36, substantially circular in cross-section, which mid section broadens outwardly and flattens toward the upper and lower portion of the dyeing or treating chamber to form the passages 37 and 38, 115 the discharge outlets 37^a and 38^a, thereof, being substantially rectangular and elongated and registering with ports or openings 39 and 40, formed in the end wall 3^a of the dyeing or treating chamber. The 120 combined inlet and outlet ports or openings 39 and 40 are disposed above and below the hanks or skeins of yarn or fiber, and such ports or openings have an area substantially equal to the cross sectional area of the 125 circular mid portion 36 of said casing, intermediate the passages 37 and 38.

130 Suitably disposed in the casing 35, preferably at the circular mid section of the same, is a propeller wheel 41, carried by a

shaft 42, which may be journaled in suitable bearings 43 and 43^a, carried by said casing, and motion to turn said shaft may be imparted by a belt 44, from any suitable form 5 of driving means; such belt passing over a pulley 45, carried by the end of said shaft 42. When driven in one direction, that indicated by the arrow *a'*, for instance, the liquid will be moved in the direction indicated by the arrows *x*; being drawn out 10 of the lower portion of the dyeing or treating chamber through the port 40, into the passage 38, and discharged by said propeller through the passage 37, and port 39, into the upper part of dyeing or treating chamber. When the wheel is driven in the direction of the arrow *b'*, the liquid will be driven out of the top of the dyeing or treating chamber in the direction of the arrows 15 *y*, indicated by dotted lines.

While I have described a propeller mounted upon a horizontal shaft and disposed in the circular mid section of the external casing for moving the liquid in the dyeing chamber, it will be understood that such propeller may be mounted upon a vertical shaft; the casing being modified accordingly, and such shaft being driven so as to move the liquid from said casing 20 through the dyeing or treating chamber in two directions. In all instances, however, such movement of the liquid takes place in a casing disposed externally of the dyeing or treating chamber.

In order that the liquid may be prevented 25 from setting up currents or eddies which would tend to pass through one portion of the hanks or skeins and omit other portions of the same, the interior of the dyeing or treating chambers is provided with a series 30 of baffle plates 46 and 47; those indicated at 46 being carried by the top or cover 7 of the dyeing or treating chamber, while those indicated at 47 being carried at the 35 bottom of the chamber. It will be understood, of course, that a greater or less number of baffle plates, capable of performing the desired function, may be employed, as desired.

While I have referred to my apparatus 40 as applied to the dyeing of hanks or skeins of yarn or other fibers, it will be understood, of course that such apparatus may be employed in the washing of skeins or hanks 45 of yarn or other fibers, or such other treatment with a liquid body to which it may be desirable to subject such skeins or hanks.

I claim:

1. In fiber-treating apparatus, the combination of a liquid-containing chamber, a 50 movable frame within said chamber comprising a plurality of fiber-carrying sticks and a plurality of rails in which the ends of said sticks are mounted, supports for the 55 ends of said rails; such supports providing for vertical movement of the rails with respect to the same, means carried by the rails for preventing endwise movement of the sticks, and means for circulating liquid in two directions through said liquid-containing chamber; the movement of the liquid in one direction tending to lift the fiber carrying sticks and the hanks or skeins supported thereby; said hanks or skeins being also lifted from said sticks by the movement 60 of the liquid. 70

2. In fiber-treating apparatus, the combination of a liquid-containing chamber, a movable frame within said chamber comprising a plurality of fiber-carrying sticks 80 and a plurality of rails in which the ends of said sticks are mounted, supports for the ends of said rails; such supports providing for movement of the rails with respect to the same, means carried by the rails for preventing endwise movement of the sticks, and means disposed externally of the apparatus for circulating liquid in two directions through said liquid-containing chamber; the movement of the liquid in one direction tending to lift the fiber-carrying sticks 85 and the hanks or skeins supported thereby; said hanks or skeins being also lifted from said sticks. 90

3. In fiber-treating apparatus, the combination of a supporting frame, a pair of rails mounted for limited vertical movement with respect to said frame, fiber-carrying sticks detachably supported in said rails, displaceable retaining means normally 100 holding said fiber-carrying sticks in place, and means for holding said stick-retaining means against movement with respect to said rails. 105

4. In fiber-treating apparatus, the combination of a liquid-containing chamber, a supporting frame removably mounted with respect to the same, a pair of rails carried by said supporting frame and mounted for limited movement with respect to the same 110 independent of any movement of the frame, fiber-carrying sticks having their ends detachably supported in said rails, displaceable plates extending longitudinally of said rails and normally retaining said fiber-carrying sticks in place, guide housings for said retaining plates in which they may be moved to active and inactive positions with respect to said sticks, and means for securing said plates to the rails in the respective 115 positions. 120

5. In fiber-treating apparatus, the combination of a pair of rails, supports for the same, in which said rails are free for limited vertical movement, a foraminous partition connected to said supports, and disposed above said movable rails, fiber-carrying sticks detachably supported in said rails, guide housings carried by said rails and secured at top and bottom to the same, dis- 125 130

- placeable retaining means carried by the rails and confined by said housings and normally holding said fiber-carrying sticks in place.
5. In fiber treating apparatus, the combination of a pair of rails, supports for the same in which said rails are free for limited vertical movement, a foraminous partition supported above said movable rails, fiber carrying sticks detachably supported in said rails, guide housings carried by said rails and secured at the top and bottom to the same, displaceable retaining means carried by the rails confined by said housings and normally holding said fiber carrying sticks in place, and means for preventing movement of said displaceable means.
6. In fiber-treating apparatus, the combination of a plurality of rails, supporting means for the ends of said rails in which said rails are free for vertical movement, and fiber-carrying sticks detachably supported in said rails, said rails and fiber-carrying sticks being bodily movable with respect to said supports under the influence of the pressure of the liquid when the latter is moving in one direction.
7. In fiber-treating apparatus, the combination of a plurality of rails, supporting means for the ends of said rails in which said rails are free for vertical movement, fiber-carrying sticks detachably supported in said rails, and a foraminous partition supported above said sticks; said partition, supporting means, rails, and sticks being bodily movable with respect to the receptacle in which such fiber is treated.
8. In fiber-treating apparatus, the combination of a plurality of rails, supporting means for the ends of said rails in which said rails are free for vertical movement, fiber-carrying sticks detachably supported in said rails, and a foraminous partition supported above said sticks; said partition, supporting means, rails, and sticks being bodily movable with respect to the receptacle in which such fiber is treated.
9. In a fiber-treating apparatus, the combination of a plurality of rails, supporting means for the ends of said rails, fiber-carrying sticks detachably supported in said rails, means for holding said sticks to the rails; said rails being free for vertical movement, a foraminous partition supported adjacent said rails; said partition, supporting means and rails being bodily movable with respect to the receptacle in which such fiber is treated, and means for moving liquid in two directions through the fiber carried by said sticks.
10. In a fiber-treating apparatus, the combination of a chamber, a plurality of rails mounted therein, supporting means for the ends of said rails in which said rails are free for vertical movement, fiber-carrying sticks supported in said rails, means for circulating liquid through said chamber; said rails and sticks being bodily movable with respect to the receptacle in which such fiber is treated when the liquid is moved in one direction, and means for preventing undue rise of the lower portion of the hanks or skeins of fiber when the fiber-carrying sticks are lifted.
11. In a fiber-treating machine, the combination of a supporting frame, a plurality of rails having apertures therein mounted for limited vertical movement with respect to said frame, fiber-carrying sticks detachably mounted in said rails with their ends resting in the apertures thereof, a locking plate, and guide housings carried by said rails and secured at top and bottom to the same for retaining said locking plate; said housings being so disposed that the locking plate will be supported thereby in a position to hold the sticks to the rails against endwise movement.
12. In a fiber-treating machine, the combination of a plurality of rails having apertures therein, fiber-carrying sticks detachably mounted in said rails with their ends resting in the apertures thereof, a locking plate, and means for holding the locking plate upon one of said rails in locking or unlocking position.
13. In a fiber-treating machine, the combination of a plurality of rails having apertures therein, fiber-carrying sticks detachably mounted in said rails with their ends resting in the apertures thereof, a locking plate, guide housings for said locking plate; said housings being so disposed with respect to the rails that the locking plates will be supported thereby in a locking position, and means for holding the locking plate upon one of said rails in locking or unlocking position.
14. In fiber-treating apparatus, a fiber-supporting structure comprising a plurality of box-like supports, a plurality of vertically movable rails having their ends mounted in said supports, removable fiber-carrying sticks mounted in said rails, and displaceable means for holding said sticks to the rails.
15. In fiber-treating apparatus, a fiber-supporting structure comprising a foraminous partition, supports connected with the same, vertically movable rails having their ends mounted in said supports, removable fiber-carrying sticks mounted in said rails, and displaceable means for holding said sticks against movement with respect to the rails.
16. In fiber-treating apparatus, a fiber-supporting structure comprising a foraminous partition, supports connected with the same, vertically movable rails having their ends mounted in said supports, removable fiber-carrying sticks mounted in said rails, displaceable means for holding said sticks to the rails, and means for locking said displaceable means in position.
17. In a fiber-treating apparatus, the combination of a closed tank having a removable top or cover, a plurality of rails, supporting means for the ends of said rails carried by said cover and removable therewith, fiber-carrying sticks detachably supported in said rails; said rails being free for vertical movement with respect to their supports, and

means for circulating liquid in two directions through the hanks or skeins supported by said fiber carrying sticks.

18. In a fiber-treating apparatus, the combination of a tank having a closed chamber with a removable top or cover, a plurality of rails mounted in said chamber, supporting means for the ends of said rails in which said rails are free for vertical movement, 10 said supporting means being connected to said cover and removable therewith, fiber-carrying sticks supported in said rails, means for circulating liquid through said chamber; said rails and sticks being bodily 15 movable with respect to the receptacle in which such fiber is treated when the liquid is circulated in one direction whereby the hanks or skeins supported by the sticks may be separated therefrom at intervals.

19. The combination, in a dyeing machine, having a closed dyeing or treating chamber, of a frame therein for supporting hanks or skeins of yarn or fiber, such frame being vertically movable under the influence 25 of the moving liquid, and means disposed externally of such chamber for moving the liquid therein in opposite directions, said liquid entering the chamber at the top and discharging at the bottom when 30 moving in one direction, and entering at the bottom and discharging at the top when moving in the opposite direction.

20. The combination, in a dyeing machine, having a closed dyeing or treating chamber, of a frame therein for supporting hanks or skeins of yarn or fiber, such frame being vertically movable under the influence 35 of the moving liquid, a compartment disposed externally of such chamber, and means in said compartment for moving the liquid in said chamber in opposite directions, said liquid entering the chamber at the top and discharging at the bottom when 40 moving in one direction, and entering at the bottom and discharging at the top when moving in the opposite direction.

21. The combination in a dyeing machine having a dyeing or treating chamber, of means disposed externally of said chamber 45 for moving the liquid therein in opposite directions, and having conduits extending to spaced points in said chamber, a frame in said chamber for supporting the treated material between said spaced points, said 50 frame being bodily movable in opposite directions within said chamber under the influence of the liquid current, the liquid being reversible through said conduit so

one conduit is employed to conduct liquid to the chamber when another is employed to conduct the liquid therefrom, and vice versa.

22. The combination in a dyeing machine having a dyeing or treating chamber, of means disposed externally of said chamber for moving the liquid therein in opposite directions, and having conduits extending to spaced points in said chamber, a frame in said chamber for supporting the treated material between said spaced points, said frame being bodily movable in opposite directions within said chamber under the influence of the liquid current, the liquid being reversible through said conduit so one conduit is employed to 70 conduct liquid to the chamber when another is employed to conduct the liquid therefrom, and vice versa, and means for deflecting and distributing in said chamber the currents issuing from said conduits. 80

23. The combination in a dyeing machine having a dyeing or treating chamber, of means disposed externally of said chamber for moving the liquid therein in opposite directions, and having conduits extending to spaced points in said chamber, said liquid moving means including valve mechanism for directing flow from one conduit to the chamber while another conduit receives flow therefrom, or vice versa, a frame in 90 said chamber for supporting the treated material between said spaced points, and being bodily movable in opposite directions within said chamber under the influence of the liquid currents therein. 95

24. The combination in a dyeing machine having a dyeing or treating chamber, of means disposed externally of said chamber for moving the liquid therein in opposite directions, and having conduits extending to spaced points in said chamber, said liquid moving means including valve mechanism for directing flow from one conduit to the chamber while another conduit receives flow therefrom, or vice versa, a frame in 100 said chamber for supporting the treated material between said spaced points, and being bodily movable in opposite directions within said chamber under the influence of the liquid currents therein, and means for 110 deflecting and distributing in said chamber the currents issuing from said conduits. 105

In witness whereof I have signed this specification.

HOWARD M. DUDLEY.
